UNITED STATES PATENT OFFICE

ELIHU D. WATT, OF LA GRANGE, ILLINOIS, ASSIGNOR TO RAYMOND CONCRETE PILE COMPANY, OF NEW YORK, N. Y., A CORPORATION OF NEW JERSEY

SHELL FOR CONCRETE FILES

Application filed July 16, 1931. Serial No. 551,100.

This invention pertains to shells suitable for driving into the ground to form molds which are later filled with concrete to form concrete piles.

5 It is customary to taper such shells and to drive them by means of collapsible tapered cores. The shells must be stiff enough radially to resist collapse due to pressure of the surrounding earth after the cores have been 10 withdrawn and before the shells have been filled with concrete, and since, for reasons of economy, the shells are of very thin material, it has been the practice either to corrugate the shells circumferentially throughout their 15 lengths, or to reinforce them by means of internal spaced-apart circumferential wires set in shallow grooves in the shells, or by a continuous wire placed in a helical groove in the shell.

20 As stated above, the shells are usually driven on tapered cores, contact with the cores, in the case of the wire-reinforced shells, being made by the wires, and the shells being forced down by virtue of the wedging action 25 of that contact. When the core becomes worn in service the wires do not contact uniformly with the core, thereby permitting the coils of wire to shift relatively to each other longitudinally of the core during the driving 30 operation, with the result that the plain portions of shell between the wires, being unable to stretch sufficiently, may be ruptured by tension between those coils of wire which shift away from each other.

35 Even if the wire-reinforced shells be successfully driven without rupture, they are still open to objection because the un-reinforced portions of the shells, between the wires, are not stiff enough to resist pressure 40 of the earth after removal of the cores and before pouring of the concrete.

Corrugated shells provide resistance against collapse but are difficult to drive. Attempts were first made to drive such shells 45 on smooth tapered cores. It was found, however, that when the shells were made of metal sufficiently thin to be commercially practical, they would sometimes burst due to the circumferential tension induced by the wedging 50 action of the tapered core. Also, the shells

were torn by obstructions, since there was no backing in the projecting corrugations to help the shell resist the obstructions. Those conditions made it necessary to drive corrugated shells by cores having collapsible 55 leaves corrugated to enter and engage the corrugations of the shell.

However, even the use of the collapsible corrugated core has not been uniformly successful. The core must collapse very materially in order to reduce its diameter sufficiently to permit ready withdrawal from the shell after driving. This means that while the core is expanded in the shell during the driving operation there are gaps of substantial 60 width between the leaves of the core. These gaps are bridged by the metal of the shell, which, being unsupported by the core, is easily torn or cut during the driving operation, thereby permitting material to enter 65 the core through the shell. This material packs between the leaves of the core, especially at its lower end, so that the core cannot be collapsed, but must be jacked out of the ground at great expense, bringing the 70 shell out with it. The present invention permits the use of a non-collapsible core, thus entirely overcoming the above objections; but if for any reason the use of a collapsible core be desired, the core needs to be only 75 slightly collapsible, thus reducing the gaps between the leaves when the core is expanded, thereby rendering the shell much less vulnerable to damage during driving.

An object of the present invention is to 80 overcome the above problems by placing a circumferential wire internally in spaced-apart corrugations of a tapered corrugated shell, and then driving the shell on a plane tapered core. If the shell be helically corrugated the corrugations may be in the form 85 of double, triple or quadruple threads and the wire may be wound in every second, third or fourth thread.

The wire engages the core, forces the cas- 90 ing into the ground, and takes the bursting strains; the corrugation containing the wire acts as a plow to push obstructions aside and thereby relieve the unreinforced corrugations 95 from much wear and tear; and the corru-

gated metal between the wires provides enough surplus metal to accommodate give-and-take so that no excessive tension is placed on the metal if the spacing between wires 5 should vary due to uneven wear of the driving core.

One embodiment of the invention is shown in the drawing, which illustrates in cross section a portion of a hollow tapered driving 10 core 10, upon which is mounted a casing 12 helically corrugated with quadruple threads, in one of which threads is placed a wire 14 of diameter at least as great as the depth of the corrugation.

15 At the top of the drawing is shown the lower end of a casing 16, similar to casing 12 and screwed into the upper end thereof, thus illustrating one method of forming shells of any desired length by coupling similar shell 20 sections together.

It is to be understood that the invention is not limited to the specific embodiment herein illustrated and described, but may be used in other ways without departure from its 25 spirit as defined by the following claims.

I claim:

1. In combination, a tapered corrugated shell, reinforcing elements in certain of said corrugations, unreinforced corrugations between said elements, said reinforcing elements serving to protect the intermediate unreinforced corrugations, and a plane tapered core engaging said reinforcing elements during the driving operation.

35 2. In combination, a tapered shell having helical multiple thread corrugations, a continuous reinforcing element in one thread of said corrugations to protect intermediate threads of said corrugations and a plane tapered core engaging said continuous reinforcing element during the driving operation.

3. In combination, a tapered shell having a helical corrugation therein, a continuous reinforcing wire in the corrugation having a 45 diameter equal to the depth of the corrugation and a smooth tapered core engaging said wire and corrugation during the driving operation, said shell having surplus metal between said corrugations constructed to expand or contract to accommodate variations in the contact of the core with the helices of the wire.

4. In combination, a pile shell having laterally continuous corrugations substantially 55 throughout its length, a driving core fitted in the shell, said shell having certain of its outer apices supported on the core by members interposed between the core and shell, said shell having the inner apices of its corrugations intermediate the members contacting the core and supported thereon.

In testimony whereof I hereto affix my signature.

ELIHU D. WATT.
